UNITED STATES PATENT OFFICE

GUSTAV EGLOFF, OF CHICAGO, ILLINOIS, AND WILLIAM R. HOWARD, OF WASHINGTON,
DISTRICT OF COLUMBIA, ASSIGNEES TO THE UNIVERSAL OIL PRODUCTS COMPANY,
OF CHICAGO, ILLINOIS, A CORPORATION OF SOUTH DAKOTA

PROCESS AND APPARATUS FOR CONVERTING HYDROCARBONS

Application filed September 1, 1922, Serial No. 585,617. Renewed June 27, 1927.

This invention relates to improvements in process and apparatus for converting hydrocarbons and is more particularly directed to the production of maximum yields of light boiling point products, in commercial quantities, from higher boiling point products.

One of the objects of the invention is to treat hydrocarbon oil under heat and pressure in such a manner as to obtain a high yield of light products therefrom. The raw oil is forced into the expansion chamber, which expansion chamber is vertical, in the present instance, and divided into two compartments by means of a vertical partition member. The raw oil there mixed with reflux condensate is forced to heating coils where it is heated to a decomposing temperature and then forced into the other compartment of said expansion chamber, where substantial vaporization takes place, the vapors rising and passing through a dephlegmator and condenser to be finally collected and the condensate collecting in the dephlegmator falling back to the compartment in the expansion chamber in which the raw oil is introduced. The expansion chamber is preferably heated, its sides being entirely surrounded by a furnace.

The single figure in the drawing is a more or less diagrammatic view, in side elevation, partly in vertical section, of our improved apparatus.

Referring in detail to the drawing, 1 designates the raw oil inlet line from any suitable source of supply (not shown) provided with the pump 2 for forcing the raw oil into the system. The raw oil is introduced into the side of the vertical expansion chamber designated as a whole by 3. As will be seen by reference to the drawing, this expansion chamber 3 is divided into two compartments 4 and 5 by the central partition member 6, the purpose of which will be hereinafter explained. The oil is subjected to heat in the compartment 4 where a small amount of the light constituents of the raw oil will vaporize. The balance of the heated raw oil will pass into coil 11 by means of pipe 7 controlled by valve 8, or may be forced into the coil under a higher pressure by means of the

pump 9 and the opening of the valves 10 and 11. In the event the pump is used, the valve 8 would be closed. The oil passes into the heating coil 12, in this instance, a coil (continuous) of 3" pipe, where it is heated to a decomposing temperature. It is not desired that any substantial vaporization take place in the heating coil 12. The heating coil 12 is mounted in the furnace 13, which is heated by means of the burner 14 and is provided with stack 15, for the escape of the spent gases of combustion.

The heated oil then passes by means of transfer pipe 16 provided with valve 17 to the compartment 5 of the expansion chamber 3, where the oil will vaporize, the vapors passing up through the pipe 18 controlled by the valve 18' to the dephlegmator 19, where a portion of them will condense. The still uncondensed vapors pass through the pipe 20 controlled by the valve 21 to the water condenser 22 seated in condenser box 23, the outlet of said water condenser being connected to the receiver 24. The receiver 24 is equipped with the gas relief pipe 25, regulated by the valve 26; the distillate drawoff pipe 27 regulated by the valve 28 and the usual pressure gauge 29. Any condensate which may settle out in the dephlegmator 19 is drawn off through the line 30, either to a point outside the system, in which event the valve 31 would be open and the valve 32 closed; or it may be returned to the compartment 4 to be mixed with the raw oil and re-treated in which event, valve 31 would be closed and the valve 32 opened. It will be noted that the hot reflux condensate coming in contact with the cold raw oil serves as a heat interchanger.

The sides of the expansion chamber 3 are preferably entirely surrounded by the fire box 13 or an additional fire box may be provided. The object of this is to form a space around the expansion chamber, or the sides thereof, in addition to that around the heating coils, through which the gases of combustion, either from the furnace 13 or in addition to the gases from the furnace 13, those produced by the use of the additional burner 33. One of the objects of heating the expan-

sion chamber is that it gives more complete and rapid vaporization. The compartment 5 of the expansion chamber is provided with the residuum drawoff 34 controlled by valve 35. 5 Suitable manhole plates 36 and 37 are provided, the former at the top of the expansion chamber proper and the latter at the bottom of the compartment 5, where the major 10 part of the vaporization is desired to take place; and where most of the carbon is precipitated. It will be understood that there will be less carbon precipitation in the compartment 4 than in the compartment 5.

One method of operating our process is as follows: The raw oil is pumped into the compartment 4 of the expansion chamber 3, where it is mixed with the heated reflux condensate returned from the dephlegmator 19. A smaller part of the raw oil will vaporize and 15 pass up to the dephlegmator, the balance, together with the reflux condensate passing out of the compartment 4 into the line 7 and through this line 7 to the heating coil 12, where it is heated to a decomposing or cracking temperature, for instance, from 750 to 850 degs. F. The heated oil is then introduced into the compartment 5 of the expansion chamber 3, where it is desired that all or substantially all of the vaporization 20 shall take place. The vapors evolved in this compartment pass up through the pipe 18 into the dephlegmator, where a portion of them will condense and be drawn off through the pipe 30 either to a point outside the system or back to the system as above described. The uncondensed vapors will pass to the condenser where they will condense and collect in the receiver. The oil, entering the compartment 5 may be subjected to a higher heat 25 than in the heating coils, say, from 800 to 900 degs. F. The compartment 4 can be heated still higher than the other one, by the use of burner 33. The system is in free communication from the pump 2 to the gas outlet valve 26, a uniform pressure of say, 125 pounds, being maintained on the entire system. Residuum will be constantly withdrawn from the bottom of the compartment 5 and may be conducted to a point outside the system or may be returned to the heating coils 30 or mixed with the raw oil in any suitable manner (not shown). This, of course, will be obvious.

The process may be operated as above described or the same temperature may be maintained throughout the system, that is, a cracking temperature, of say, from 750 to 900 degs. F. Or differential pressures may be maintained by proper manipulation of the valves shown. For instance, the heating coils may be maintained under a pressure of say, 300 pounds, the expansion chamber under 150 pounds pressure, the dephlegmator under 100 pounds and the condenser and receiver 35 under 50 pounds pressure. In the event dif-

ferential pressures are used, the pump 9 will be operated to force the reflux condensate and raw oil from the compartment 4 to the heating coils, the valves 10 and 11 being opened the valve 8 closed. The process may be operated either as a continuous or as a batch process.

Using a mid-continent gas oil of say, 32 degs. Baumé as a charging stock, and maintaining the temperature and pressure first described, a yield of from 35 to 60% of commercial Navy specification gasoline may be obtained. The gravity of the residuum withdrawn through the pipe 34 may be controlled and regulated so that a maximum 40 yield of desirable light products may be obtained, thus increasing the final yield of light products, based on the charging stock.

We claim as our invention:

1. A process of cracking petroleum oil, 45 consisting in passing the oil through a heating coil and heating it to a conversion temperature, preventing substantial vaporization in the heating coil, passing the heated oil to an enlarged expansion chamber where vaporization takes place, in preventing the return of any unvaporized oil from said chamber to the heating coil, in withdrawing the vapors from said expansion chamber and subjecting them to dephlegmation and returning selected portions of the reflux condensate to the expansion chamber, maintaining said reflux condensate in a pool separate from the heated oil introduced to the chamber from the heating coil, introducing charging oil to be treated into the pool of reflux condensate and forcing the combined mixture to the heating coil.

2. In an apparatus for cracking oil, the combination with a heating coil mounted in a furnace, communicating with a vertical expansion chamber, a vapor drawoff therefrom, dephlegmating means communicating with the vapor drawoff, longitudinally extending partitioning means within the expansion chamber dividing same into a plurality of compartments, means for returning selected portions of the reflux condensate to one compartment, an inlet for fresh charging stock communicating with the reflux compartment and means for introducing the combined mixture to the heating coil.

3. In an apparatus for cracking oil, the combination with a heating coil mounted in a furnace, communicating with a vertical expansion chamber, a vapor drawoff therefrom, dephlegmating means communicating with the vapor drawoff, longitudinally extending partitioning means within the expansion chamber dividing same into a plurality of compartments, means for returning selected portions of the reflux condensate to one compartment, an inlet for fresh charging stock communicating with the reflux compartment and means for introducing the combined mixture to the heating coil.

ture to the heating coil, said means comprising a pump interposed in the connecting line between the reflux compartment and the heating coil, and means for maintaining a super-atmospheric pressure on the oil and vapors under treatment.
